(57) CLAIM

The ornamental design for an interface cover, as shown and described.

DESCRIPTION

FIG. 1 is a front perspective view of an interface cover showing our new design;

FIG. 2 is a right side elevational view of the interface cover shown in FIG. 1;

FIG. 3 is a front elevational view of the interface cover shown in FIG. 1;

FIG. 4 is a rear elevational view of the interface cover shown in FIG. 1;

FIG. 5 is a left side elevational view of the interface cover shown in FIG. 1;

FIG. 6 is a top plan view of the interface cover shown in FIG. 1; and,

FIG. 7 is a bottom plan view of the interface cover shown in FIG. 1.

It will be understood that the dashed lines presented in the drawings are for illustration only, and do not form a part of the claimed design.
